ATTORNEY

WITNESS:

Patented July 28, 1925.

UNITED STATES PATENT OFFICE.

BRITTON A. VAN NAUKER, OF FAYETTEVILLE, NEW YORK.

SPARK PLUG.

Application filed September 1, 1923. Serial No. 660,643.

To all whom it may concern:

Be it known that I, BRITTON A. VAN NAUKER, a citizen of the United States, residing at Fayetteville, in the county of Onondaga and State of New York, have invented new and useful Improvements in Spark Plugs, of which the following is a specification.

This invention relates to igniters, particularly to spark plugs, and has for its object the provision of a spark plug which is so constructed as to prevent the accumulation of carbon which so quickly fouls and short circuits ordinary plugs.

Another object is the provision of a spark plug in which one electrode is of a ring like nature so as to provide a multiplicity of points at which the spark may jump.

Still another object is the provision of a plug in which the central electrode is entirely contained within the skirt to accomplish the manifest advantage of providing a larger space for combustion so that a smaller deposit of carbon will be left.

An additional object is the provision of a device of this character which will be simple and inexpensive in manufacture, positive in action, efficient and durable in service and a general improvement in the art.

With the above and other objects and advantages in view the invention consists in the details of construction to be hereinafter more fully described and claimed and illustrated in the accompanying drawings, in

which:

The figure shows a longitudinal section through the plug.

Referring more particularly to the drawings the numeral 10 designates the metallic body or shell which is formed with a bore 11 and a counter-bore 12 which is threaded. At one end, the end opposite the counter-bore, the body is prolonged to define a skirt 13 which is threaded for engagement within the spark plug receiving hole of an engine.

Disposed within this body is the usual core 14 of insulating material such as porcelain or the like and this core has one end extending within the bore 11. Intermediate its ends the core is formed with a flange or enlargement 15 engaged within the counter-bore 12, and located at opposite sides of this enlargement are the usual packing gaskets 16. A pack nut 17 surrounds the core and is threaded into the counter-bore 12 for rigidly securing the core in position.

The numeral 18 represents the central electrode which passes axially through the core and which is equipped with the usual clamping nut 19 and binding nuts 20 for making connection with the current carrying wires of the engine. The essence of the invention lies in the provision of a metallic ring 21 which is sweated, shrunk or otherwise secured within the skirt 13 and which has its face toward the end of the skirt concaved as clearly disclosed so that any oil accumulating on this ring will flow toward the wall of the skirt. This ring has a central opening 22 which is beveled or tapered and which conformingly fits against the adjacent end of the core. The fit is of such a nature as to permit expansion of the parts when a high degree of heat is reached in the cylinder in which the plug is used, but it is intended that the fit be sufficiently close as to exclude oil and gas from the space between this ring or disk and the major portion of the core. The central electrode 18 passes through this opening or hole and projects slightly beyond the ring or disk, and in actual practice it is preferable that the hole 21 be of such a diameter as to provide the usual distance between its wall and the periphery of the central electrode, the general practice being to provide a gap of one thirty-second of an inch, though the exact distance may be varied within certain limits.

The plug is of course used like any other plug but has the great advantage of remaining clean and operative for a greater length of time.

While I have shown and described the preferred embodiment of my invention it is of course to be understood that I reserve the right to make such changes in the form, construction and arrangement of parts as will not depart from the spirit of the invention or the scope of the subjoined claim.

Having thus described my invention I claim:

In a spark plug, a metallic body having one end exteriorly threaded for engagement within the spark plug receiving hole of an engine, said body being formed with a bore cylindrical and smooth throughout and further formed with a threaded counter bore, an insulating core located within the body and having an enlarged portion seated within the counter bore, a packing nut member screwed into the counter bore and en-

gaging the enlarged portion of the core, the end of the core nearest the exteriorly threaded portion of the body being tapered, a central electrode extending through the core and projecting beyond the end thereof, said core and electrode terminating well within the body and a ground electrode formed as a ring member fitting the inter-

mediate portion of the bore and having an opening conformingly engaging and receiving the tapered end of the core, the lower side of the ring member being beveled outwardly and downwardly. 10

In testimony whereof I affix my signature.

BRITTON A. VAN NAUKER.
